UNITED STATES PATENT OFFICE.

WILLIAM T. CARNES, OF KANSAS CITY, MISSOURI, ASSIGNOR TO CARNES ARTIFICIAL LIMB COMPANY, OF KANSAS CITY, MISSOURI.

PHONOGRAPH.

Application filed December 16, 1922. Serial No. 607,370.

To all whom it may concern:

Be it known that I, WILLIAM T. CARNES, a citizen of the United States, residing at Kansas City, in the county of Jackson and 5 State of Missouri, have invented certain new and useful Improvements in Phonographs; and I do hereby declare the following to be a full, clear, and exact description of the invention, such as will enable others 10 skilled in the art to which it appertains to make and use the same, reference being had to the accompanying drawings, and to the letters of reference marked thereon, forming part of this specification.

15 My invention relates to phonographs and the object thereof is to provide a resonator or horn which projects the tones through the bottom of the machine case. Also to provide a mute or muffler and controlling 20 mechanism therefor which can be positioned close to or spaced away from the resonator, or which can be used as a deflector to deflect the sound laterally when desired.

The features of my invention are herein- 25 after described and pointed out, and are illus- trated in the accompanying drawings, in which,

Figure 1 is a side elevation of my im- 30 proved resonator and mute mechanism with the casing of the machine outlined there- about.

Figure 2 is a front view of the same.

In these drawings A indicates the horn or resonator of a phonograph; B indicates 35 the usual tone arm; B' indicates a sound box of ordinary construction; and C indicates a turn table.

The horn or resonator A is so formed that the bell portion A' thereof will project the 40 sound therefrom through an opening in the bottom D of the case E of the machine. In order to reduce the volume of tone, as may be desired, I provide an adjustable mute or muffler plate F, which is suspended adja- 45 cent to the bell portion A' of the resonator A by means of the side arms F'. The upper ends of the arms F' are pivoted to swinging arms G. These swinging arms G are se- 50 cured upon a transverse shaft G' by means of pins g, see Fig. 2, said shaft G' being mounted in suitable bearings H which are secured to the casing E of the machine, so that the swinging arms G will swing in unison and raise and lower each arm F' 55 simultaneously. J indicates a swinging arm

which is pivoted to bracket J' secured to the casing E of the machine, the free end of which is connected with one of the swinging arms G by means of a link bar J² which is pivoted on the arms J and G. Pivoted 60 on the arm J is a lever K to the lower end of which is pivoted a link bar L, the opposite ends thereof being pivoted to one of the bars F', so that by means of the lever K the swinging arms G can be operated to lower 65 the muffler plate F as shown by broken lines f and to swing said plate laterally as shown by broken lines f' f' in Fig. 1. To counter- balance the muffler mechanism hereinbefore described, I provide a weight M see Fig. 2 70 from which a cord M' extends on a pulley M² and thence down to one of the swinging arms G to which said cord is secured. I also provide a tubular guide N for the weight M, the upper end of which is secured 75 to the upper board of the machine frame E by means of an ear m, the pulley M being pivoted in the upper end of said guide.

From the foregoing description it will be 80 obvious that the sound will be thrown downwardly by the resonator and that the muffler plate F can be spaced with relation to the resonator as may be desired, and that by means of the counter weight it will be main- 85 tained in the desired position. Also that it can be swung laterally to deflect the sound toward the front or rear as may be desired.

Having thus shown and described my in- 90 vention so as to enable others to utilize the same I do not desire to be limited to the exact construction of mechanism shown and described, as many modifications can be made therein without departing from the scope of my invention, therefore what I claim as new and desire to secure by Let- 95 ters Patent is:

1. In an apparatus of the class described, sound reproducing mechanism, a case enclosing the same, a resonator, a muffler plate, means to move said plate away from and toward said resonator, and means to swing 100 said plate laterally.

2. In an apparatus of the class described, sound reproducing mechanism, a case enclosing the same, a resonator, a muffler plate, arms on said plate at opposite sides of said resonator, swinging bars pivoted to said case and to said arms, another swinging bar pivoted to said case, a link connecting the free end of said last mentioned bar and the 110

first mentioned bar, a hand operated lever pivoted to the last mentioned bar, a link connecting said lever with said arms, and means to counter balance said muffler plate and operating mechanism.

3. In an apparatus of the class described, sound reproducing mechanism, a case enclosing the same, a resonator, a muffler plate, arms secured on said plate at opposite sides

of said resonator, vertically swinging bars pivoted to said case and to said arms, means to counter-balance said muffler plate and bars, and lever and link mechanism to depress said muffler plate and simultaneously cause the same to swing laterally.

15 In testimony whereof I affix my signature.

WILLIAM T. CARNES.
